UNITED STATES PATENT OFFICE

1.986.302

Elmer B. Stone, New Britain, Conn., assignor to
The American Hardware Corporation, New
Britain, Conn., a corporation of Connecticut

Application December 5, 1930, Serial No. 500,223

3 Claims. (Cl. 70—108)

My invention relates to that class of locks above mentioned, and an object of my invention, among others, is the production of a lock of this type that is provided with means for guarding it against tampering or unlocking without the use of a key.

One form of a lock embodying my invention and in the construction and use of which the objects herein set out, as well as others, may be attained, is illustrated in the accompanying drawing in which—

Figure 1 is a side view of a padlock embodying my invention.

Figure 2 is a view in section through the lock 15 on a plane passing through the center of the shackle arms as denoted by the dotted line 2-2 of Figure 5.

Figures 3 and 4 are detail views in section illustrating the camming action of the shackle on the locking bolt.

Figure 5 is an end view of the lock.

Figure 6 is a view in section on a plane denoted by the dotted line 6-6 of Figure 2.

Figure 7 is an end view, scale enlarged, of the locking bolt and key plug.

Figure 8 is a view in section on a plane denoted by the dotted line 8-8 of Figure 7.

Figure 9 is an isometric view illustrating the plug, actuating spring and bolt in a disassembled arrangement.

In the accompanying drawing the numeral 10 indicates the case of my improved lock that, as to its general construction, may be of an ordinary type, having openings for the branches of a shackle, for a key plug, and for tumblers acting in connection with said plug. The shackle has an arm 11 pivotally secured within the case near one edge thereof and seated upon a spring 12, while the other, short arm 13 of the shackle is formed to engage within a recess 14 projecting inwardly from the end of the case near one edge thereof. All the parts thus far described may be of old and well known construction and, except for features to be hereinafter mentioned, form no part of the present invention.

45 form no part of the plug. A key plug 15 is rotatably secured within the case in any ordinary manner, this plug having the usual slot for the reception of a key and it is provided with pin tumbler members to act in connection with similar members in the case to 50 permit rotation of the plug when the pin tumblers are properly positioned by a key in a manner that will be readily understood.

55 In locks of this type it has often been found possible, by means of blows properly delivered

against the case, to release the member engaging the short arm of the shackle and thereby enable the lock to be opened without the use of a key, and it is to avoid an operation of this sort that the present invention has been made. In accomplishing this purpose I provide a locking bolt rotatably mounted on the end of the key plug, in that form of the structure herein shown the plug 15 being cut away on one side at its end as at 16, and it is provided in this end with a recess 17 from the bottom of which a stud 18 projects. An actuating lug 19 extends from this end of the plug, as shown in Fig. 9 of the drawing.

A locking bolt 20 is pivotally mounted on the stud 18, this bolt resting on the end of the plug 15. This bolt has a notch 21 cut in one side to receive the lug 19, which lug acts against shoulders at opposite sides of the notch. Said bolt has a locking lip 22 that is adapted to engage with in a notch 23 in the side of the short arm 13 of the shackle near its end. A cam 24 is formed on said lip for engagement by a cam 25 on the end of the short arm of the shackle. A spring 26 is placed in the recess 17, one end of the spring being inserted in a hole in the bottom of said recess and the other end being inserted into a hole 27 in the bolt 20 for the purpose of holding the bolt normally in its locked position.

In the operation of the parts the bolt is held by the spring so that the locking lip 22 is normally engaged in the notch 23 in the end of the short arm 13 of the shackle. A key having been inserted in the plug and the tumblers properly positioned to permit rotation of the plug, such rotation will carry the actuating lug 19 against a shoulder at the end of the notch 21, thereby rotating the locking bolt to disengage the lip 22 from the notch 23 in the shackle arm, thus permitting the shackle to be disengaged from its opening in the case under the influence of the spring 12. 30 35 40

In order to remove the key from the plug it will now be necessary to reverse the rotation of the plug to its normal position, wherein the lip 22 will be projected into the path of movement of the short arm 13 of the shackle when it shall be again projected into its opening, as in locking of parts. In this locking movement the cam 25 on the end of the shackle engages the cam 24 on the locking bolt rotating the latter against the tension of the spring 26 and permitting the shackle to be placed in locking position. Just as soon as this position is reached the spring 26 will rotate the bolt to engage the lip 22 with

the notch 23 in the shackle arm, thereby holding the latter in its locked position.

As an aid to operation of the key plug 15, I employ a spring 28 surrounding the plug, one end of the spring being engaged in an opening in the lip of the plug, and the other end of the spring being engaged in an opening in the case 10. The action of the spring is to return the plug to its normal position when it has been turned from that position in the use of a key to unlock the shackle, the key plug being thus always in position to permit removal from or insertion of a key into the plug.

In accordance with the provisions of the patent statutes, I have described the principles of operation of my invention, together with the device which I now consider to represent the best embodiment thereof, but I desire to have it understood that the device shown is only illustrative and that the invention may be carried out by other means and applied to uses other than those above set out.

I claim:

1. A padlock including a case, a shackle mounted in the case and having a locking notch, a key plug round in cross section rotatably mounted in the case, a locking bolt conforming in cross sectional shape substantially to that of the key plug, of substantially the same diameter and forming the tip of the plug, said bolt being rotatably mounted on the end of said plug and having a notch in its side surfaces, a pin projecting from the key plug into said notch to effect movement of said bolt and to permit movement of the bolt independently of the key plug out of the path of the shackle in its closing movement, a spring secured to the plug and exerting force upon the bolt to rotate it to

engage the end of said notch with said pin, and a lip on said bolt to engage the notch in said shackle.

2. A padlock including a case, a shackle mounted in the case and having a locking notch, a cylindrical key plug rotatably mounted in the case with a recess in its end, and a stud projecting from the bottom of said recess, a pin projecting from the end of the plug, a locking bolt having peripheral portions conforming in shape to the round peripheral parts substantially of said plug and of substantially the same diameter rotatably mounted on said stud and comprising the tip of said plug, said bolt having a recess within which said pin projects, a spring located in the recess in the end of the plug and surrounding said stud, one end of the spring engaging a hole in the plug and the other end engaging a hole in said locking bolt, and a lip on said locking bolt to engage said notch in the shackle.

3. A padlock including a case, a shackle mounted in the case and having a locking notch, a cylindrical key plug rotatably mounted in the case, a locking bolt having peripheral portions conforming in shape substantially to the shape of the round portions of the key plug and of substantially the same diameter rotatably mounted on the end thereof and forming its tip, said tip and plug being cut away on one side to form a recess to receive the end of said shackle, a lip on said locking bolt to engage the notch in said shackle, a spring exerting its force in opposite directions on said plug and said locking bolt, and means for limiting rotating movement of said bolt independently of said plug.

ELMER B. STONE.
